UNITED STATES PATENT OFFICE.

ERNEST S. JOHNSON, OF WEBSTER CITY, IOWA, ASSIGNOR OF ONE-HALF TO WILLIAM B. ROOD, OF WEBSTER CITY, IOWA.

STOCK-WATERING DEVICE.

15,139.

Specification of Reissued Letters Patent. Reissued July 5, 1921.

Original No. 1,287,696, dated December 17, 1918, Serial No. 219,057, filed February 25, 1918. Application for reissue filed April 9, 1920. Serial No. 372,718.

To all whom it may concern:

Be it known that I, ERNEST S. JOHNSON, a citizen of the United States of America, and a resident of Webster City, Hamilton county,

5 Iowa, have invented certain new and useful Improvements in Stock-Watering Devices, of which the following is a specification.

My invention relates to improvements in stock watering devices, and the object of my 10 improvement is to furnish a simple, convenient watering tank and holder, provided with removable drinking chambers for a plurality of stock, and arranged interiorly to permit water to be warmed in the tank 15 and the chambers, while permitting cleaning of the chambers at any time.

This object I have accomplished by the means which are hereinafter described and claimed, and which are illustrated in the accompanying drawings, in which:

Figure 1 is a vertical transverse medial section of my improved stock watering device.

Fig. 2 is a vertical longitudinal medial section of the same.

Fig. 3 is a top plan view of the device, with the cover, the tank and one of the chamber-hoods removed.

Fig. 4 is a perspective view of the tank, 30 showing its delivery device partially broken away.

Fig. 5 is a perspective view of the receptacle.

Fig. 6 is a perspective view of one of the chamber-hoods.

Similar numerals of reference denote corresponding parts throughout the several views.

The numeral 1 denotes a hollow rectangular casing, provided with a removable cover 2 closing its open top. In one end of the casing is a door-opening 18 having at the sides guides 17 to receive the side edges of a slide 3. Both the cover 2 and the slide 3 have ventilating orifices 16 and 15 respectively. A lamp, as indicated in Fig. 1, may be introduced into the casing through said doorway to rest on the bottom plate thereof to warm the contents of the drinking chambers and the supply-tank above. The bottom plate of the casing has orifices 19 to permit drainage.

Referring now to Fig. 1, the numeral 4 denotes a rectangular opening, there being

such openings on opposite sides of said casing. A shallow open top pan or receptacle 5 is positioned across the interior of the casing, and has its end edges 24 inverted and fitted removably over the lower edges of said openings to support said receptacle suspensively. Each end of said receptacle, within said casing, is partially inclosed by a chamber-hood 6, of the form shown in said Fig. 6, having its lower rectangular end dipped within the receptacle part way therethrough, each hood having inverted edge parts 20 and 21 which pass through the opening 4 to engage the outer surface of the casing to hold the hood in position. On the inner face of each end-wall of the casing is fixed a supporting bar 7 on whose middle is a U-shaped bearing 8 to detachably receive the outwardly projected ends or pintles of a cylindrical axis 9 fixed axially through a cylindrical supply tank or vessel 10. This tank 10 is imperforate except for some orifices 14 placed in alignment longitudinally near together on the lower side of the tank, and which serve as receiving ports for water when the orifices are uppermost, and as delivery ports for the water when the tank is inverted to the position shown. Surrounding these orifices is a boxing 11 inclosed against the tank at the sides and ends, its bottom partially closed at 12, and having a raised wall 13, which, however, extends only part way toward the tank. When the tank 10 is placed inverted after filling with water in the casing to have its pintles rest in the bearings 8, the boxing 11 extends part way down into the receptacle 5 midway between the hoods 6. At one end of the tank on its cylindrical outer wall, spaced lugs 23 have aligned orifices to receive a rod 22, which can be slid along to rest on the ledge of the bar 7 to hold the tank steady.

The inclosed spaces in the receptacle 5 at its ends, serve as drinking chambers for animals, who drink through the openings 4, and the drinking chambers are kept supplied by the tank 10, since the water level in the receptacle is determined by the delivery of water from the tank by way of the boxing 11 as governed by the limiting wall 13 and the depending lower end of said boxing within said receptacle. It will be seen that all the parts are readily assembled or disassembled for cleaning or repair, the device is

compact, can be used by a plurality of animals at once, and the contents of the receptacle and tank kept warm in cold weather, by the lamp within the casing.

5 Since the tank 10 is rotatable upon its pintles 9, after the slide pin 22 has been pushed in, and one of the hoods 6 have been removed, the tank may be rocked upwardly in order to place its boxing 11 uppermost, 10 and then water may be introduced into the tank by way of the orifices 14, and when filled, the tank may be rocked reversely to locate the boxing again within the receptacle 5, and the hood 6 replaced, and the 15 tank is then held by sliding the pin 22 outwardly to rest upon the support 7, although, of course, without that, the boxing could not be rotated past the depending hoods 6. Warm air from the lamp 25 circulates 20 through the casing 1, passing upwardly about the tank 10 and heats the spindles and bearings or trunnions, thus preventing them from becoming inoperable or obstructed by climatic conditions, the openings 15 and 16 25 in the casing and its cover permitting a proper ventilation.

Having now described my invention, I claim:

1. In a stock watering device, a casing 30 having openings in opposite sides, an open top receptacle positioned across the interior of the casing from one opening to the other, and an inverted vessel having common receiving and delivery ports and having a pendant chamber receiving from said ports and having a channel delivering into said receptacle, including an elevated part of the channel restricting the delivery therefrom, said chamber having part of its outer closure 35 wall removed and having a longitudinal ledge extending as a partial septum across it spaced from the vessel.

2. In a stock watering device, a casing having openings, an open top receptacle positioned within said casing communicating with said openings and having end flanges hung detachably on the lower margins of said openings, hoods partially inclosing end parts of said receptacle removably in communication with both said openings and the receptacle and removable outwardly by way of said openings, and a rotatable tank mounted in said casing above said receptacle, and having a common receiving and delivery 55 port adapted to be used to fill the tank when rotated upwardly, and to deliver its contents into said receptacle when rotated downwardly.

3. In a stock watering device, a casing 60 having openings, an open top receptacle positioned within said casing and communicating with said openings, hoods partially inclosing end parts of said receptacle removable outwardly and being in communication with 65 said openings and said receptacle, and a

tank rotatably mounted in the casing above said receptacle having a common receiving and delivery opening, and having a channeled boxing about said opening extending outwardly into said receptacle and between 70 said hoods and limited in side movement by the latter, the hoods being removable to permit the tank to be rotated upwardly to place said boxing upwardly with its channel and the tank opening in a filling position.

4. In a device of the character described, a supporting casing, a watering trough therein, said casing having an opening through which ready access may be had to said trough, a water tank for automatically 80 feeding water to the trough rotatably supported on trunnions entirely within the casing, heating means within the casing for causing heat to pass around the trough, tank and said trunnions, and enable the tank to 85 be easily rotated at all times.

5. In a device of the character described, a watering trough, a container in which said trough is mounted and through which access may be had to the trough, a water feeding tank, rotatably supported adjacent the trough on trunnions and in a position to automatically feed water to the trough, the walls of said trough being in part spaced 90 from the walls of said container, and means for maintaining heat around the trough, the trunnions and water feeding tank, and preventing water in the tank and trough from freezing and the trunnions from becoming frozen or stuck in their bearings.

6. In a device of the character described, a container provided with oppositely positioned drinking openings, a watering trough between the openings and resting on the material forming the lower edges of said openings, a water holding tank rotatably mounted in the sides of the container and provided with means for automatically feeding water to the trough in an amount not sufficient to overflow the same, a heater, said trough, tank and heater being so arranged within the container that heat will pass up around the trough and tank and its bearings to warm the water and maintain the tank in an easily rotatable condition in cold weather.

7. In a device of the character described, a container, in which each of two opposite walls has a drinking opening formed therein, a pan supported between said openings with its bottom elevated a substantial distance above the bottom of the container, a rotatable tank in the container for automatically feeding to and maintaining fluid in the pan, a heater below said pan to prevent freezing of the water, said rotatable 125 tank being so arranged relative to said container that heat will reach the rotatable mounting of said tank and prevent freezing thereof.

8. In a device of the character described,

an angular container having a pair of drinking openings in opposite walls spaced from the bottom thereof, a pan supported between said openings with its bottom elevated above 5 the bottom of the container, hoods extending inwardly and downwardly from said openings to limit the escape of heat from the container, a rotatable tank in the container for automatically feeding fluid to the 10 pan in an amount insufficient to cause over-

flow thereof, a heater in the container, in position to heat the fluid in said pan and tank, and the bearings of the tank, and enable the tank to be easily rotated in cold weather, and a door in one wall of the container whereby access may be had to the heater. 15
